Primary Examiner—Antoine D Davis*(74) Attorney, Agent, or Firm*—Bruce S. Shapiro; John Yun; Wesley W. Muller(57) **CLAIM**

The ornamental design for a drill, as shown and described.

DESCRIPTION

FIG. 1 is a left/front perspective view of a drill.

FIG. 2 is a right side view thereof.

FIG. 3 is a left side view thereof.

FIG. 4 is a top side view thereof.

FIG. 5 is a bottom side view thereof.

FIG. 6 is a front view thereof.

FIG. 7 is a rear view thereof.

FIG. 8 is a left/front perspective view of a drill.

FIG. 9 is a right side view thereof.

FIG. 10 is a left side view thereof.

FIG. 11 is a top side view thereof.

FIG. 12 is a bottom side view thereof.

FIG. 13 is a front view thereof.

FIG. 14 is a rear view thereof.

FIG. 15 is a left/front perspective view of a drill.

FIG. 16 is a right side view thereof.

FIG. 17 is a left side view thereof.

FIG. 18 is a top side view thereof.

FIG. 19 is a bottom side view thereof.

FIG. 20 is a front view thereof.

FIG. 21 is a rear view thereof.

FIG. 22 is a left/front perspective view of a drill.

FIG. 23 is a right side view thereof.

FIG. 24 is a left side view thereof.

FIG. 25 is a top side view thereof.

FIG. 26 is a bottom side view thereof.

FIG. 27 is a front view thereof.

FIG. 28 is a rear view thereof.

FIG. 29 is a left/front perspective view of a drill.

FIG. 30 is a right side view thereof.

FIG. 31 is a left side view thereof.

FIG. 32 is a top side view thereof.

FIG. 33 is a bottom side view thereof.

FIG. 34 is a front view thereof.

FIG. 35 is a rear view thereof.

FIG. 36 is a left/front perspective view of a drill.

FIG. 37 is a right side view thereof.

FIG. 38 is a left side view thereof.

FIG. 39 is a top side view thereof.

FIG. 40 is a bottom side view thereof.

FIG. 41 is a front view thereof; and,

FIG. 42 is a rear view thereof.

The broken line showing of the trademark is included for the purpose of illustrating non-claimed subject matter and forms no part of the claimed design.
